UNITED STATES PATENT OFFICE

169,554

FIRST-AID KIT OR SIMILAR ARTICLE

William C. Littlejohn, Los Angeles, Calif., assignor to Regis Plastics Corporation, Beverly Hills, Calif., a corporation of California

Application February 9, 1953, Serial No. 23,482

Term of patent 3½ years

(Cl. D58—2)

To all whom it may concern:

Be it known that I, William C. Littlejohn, a citizen of the United States of America, and a resident of Los Angeles, in the county of Los Angeles, and State of California, have invented a new, original, and ornamental Design for a First Aid Kit or Similar Article, of which the following is a specification, reference being had to the accompanying drawing forming part thereof, in which:

Figure 1 is a side elevation of a first aid kit or similar article, showing my new design;

Fig. 2 is an end view taken from the left-hand side of Fig. 1;

Fig. 3 is an end view taken from the right-hand side of Fig. 1; and

Fig. 4 is a plan view thereof.

I claim:

The ornamental design for a first aid kit or similar article, substantially as shown.

WILLIAM C. LITTLEJOHN.
